A. B. MITCHELL.
REFLECTOR FOR GAS LAMPS,
APPLICATION FILED AUG. 21, 1916.

Patented Dec. 25, 1917.

UNITED STATES PATENT OFFICE.

ARTHUR B. MITCHELL, OF BIRMINGHAM, ALABAMA.

REFLECTOR FOR GAS-LAMPS.

1,251,084.

Specification of Letters Patent. Patented Dec. 25, 1917.

Application filed August 21, 1916. Serial No. 116,050.

To all whom it may concern:

Be it known that I, ARTHUR B. MITCHELL, a citizen of the United States of America, residing at Birmingham, in the county of 5 Jefferson and State of Alabama, have invented certain new and useful Improvements in Reflectors for Gas-Lamps, of which the following is a specification.

My present invention relates to an improvement in reflectors for miners' acetylene gas lamps which is especially designed to protect the flame against being extinguished by air currents coming from any direction, and particularly by strong air currents blowing 15 directly against the burner flame.

The reflector, in accordance with my present invention, is provided with a raised guard surrounding the burner tip and having air ports so arranged as to permit the 20 direct currents of air to pass inwardly through the guard and into the burner chamber below the flame where a reverse outward current of air is set up to protect the flame. Preferably the guard is extended well 25 beyond the burner tip so as to directly shield it from lateral drafts, and it is preferably contracted to form a restricted flame throat.

My invention further comprises the novel details of construction and arrangements of 30 parts, which in their preferred embodiment only are hereinafter more particularly described and illustrated in the accompanying drawings which form a part of this specification, and in which:—

35 Figure 1 presents the reflector and burner in front elevation.

Fig. 2 is a cross sectional view on the line 2—2 of Fig. 1.

Similar reference numerals refer to similar 40 parts throughout the drawings.

I have illustrated my invention applied to a miner's acetylene gas burning lamp 1, the design of which is typical of any gas burning lamp. This lamp comprises a burner tube 2 45 leading horizontally through its side wall and terminating in a burner tip 3 which has lateral air ports 4 disposed without the lamp and adjacent to the tip. There may be any desired number of holes 4 and they preferably 50 surround the burner. The burner tip passes through a circular base 5 shaped to conform to the side wall of the lamp to which it is soldered or made fast in any desired manner. Upon this base is mounted 55 the reflector preferably of a dish shaped or bell-like character and which preferably

comprises a flattened back portion 6 which rests on and is rigidly attached to the base 5. Around the outer edge of this back portion 6 is an annular convexly curved reflecting wall 8 and around the inner edge of the back is the guard formed by an outer annular wall 9 which curves outwardly and over and inwardly to form a contracted neck or throat 10 opposite the tip 3, whence the 65 metal is drawn in on a reverse curve inwardly as the inner wall 11 of the guard, which at its inner end is curved toward and joins the burner tube and, if desired, may be spot welded or secured to the base 5. In 70 the outer portion of the wall 9 of the guard, I provide a plurality of air inlet ports 12 surrounding the guard and adapted to admit the air currents coming directly from the front into the air distributing chamber 13 75 formed between the walls 9 and 11 of the guard from whence the air flows from a series of ports 14 in the wall 11 into the air chamber 15 surrounding the tip. This chamber is bulbous or pear shaped in its preferred 80 form. These ports 14 are preferably arranged so that the air enters the chamber 15 therethrough in position to have access to the burner through air ports 4 and to create a counter-draft outward toward the throat 85 10 which will protect the flame at the tip from being extinguished by a direct draft blowing toward the throat. Preferably the holes 12 and 14 are relatively staggered so that the entering air becomes distributed 90 through the chamber 13 and is moved outwardly through the holes 14 responsive to the pressure in the chamber 13 caused by the wind. Moreover, it will be noted that the wall 11 is so curved as to prevent the 95 tendency of direct drafts between the ports 12 and 14.

The reflector may be provided with air exhaust holes wherever suited, such being exemplified by the series of holes 16 surrounding the base of the flange 8.

In operation, the guard positively protects the burner tip from any wind currents except those coming head on into the reflector and under such conditions the contracted 105 neck 10, as well as the counter-currents induced by the circulation through the ports 12 and 14, as indicated by the arrows in Fig. 2, will effectively protect the flame at the tip and will prevent the lamp becoming extinguished.

The guard walls are shown as formed in-

tegrally with the reflector but they may be made and applied in any suitable manner so long as they form the desired guard surrounding the tip.

- 5 The shape of the reflector proper may be widely varied and it may be mounted in any well known manner on the lamp.

The convex curvature of the flange 8 is preferable as it tends to avoid a congestion 10 of air at the back of the reflector. The curvature of the wall 9 tends to deflect the air currents toward the exhaust ports 16, which may be arranged in any convenient manner near the outer margin of the back 6. It is 15 not essential that the back wall 6 be flat but should not slope inwardly and away from the ports 16 as that might tend to deflect the air currents from the exhaust ports 16.

Having thus described my invention, 20 what I claim as new and desire to secure by Letters Patent, is:—

1. In a concave reflector, a tip projecting from its center substantially axially thereof, a guard surrounding the tip and formed by 25 spaced walls connected at their outer ends, there being draft holes in the outer and inner walls to provide an air circulation outwardly around the tip.

2. In a reflector, a burner tip projecting 30 therethrough, and a guard for the tip formed by an annular chamber surrounding the tip and closed at its rear end, there being ports to admit air near the outer portion of the outer wall and other ports to deliver the 35 entering air to the burner tip near its outer end.

3. In a reflector, a burner tip projecting therethrough, and a guard for the tip formed by an annular chamber surrounding the tip 40 and closed at its rear end, there being ports to admit air near the outer portion of the outer wall and other ports to deliver the entering air to the burner tip near its outer end, and said tip having side ports for air.

45 4. In combination, a reflector, a burner tip projecting therethrough, walls projecting outwardly from the reflector and forming an annular chamber which surrounds and guards the tip, said chamber being closed 50 except for a series of marginal air ports about its outer wall, and a series of ports about its inner wall which is spaced from the burner tip to form an air space.

5. In combination, a reflector, a burner tip 55 projecting therethrough, walls projecting outwardly from the reflector and forming an annular chamber which surrounds and guards the tip, said chamber being closed

except for a series of marginal air ports about its outer wall, and a series of ports 60 about its inner wall which is spaced from the burner tip to form an air space, the inner wall being contracted outwardly to form a restricted flame throat beyond and in line with the burner tip. 65

6. In combination, a dish shaped reflector, a burner tip projecting through the reflector in line with its axis, a guard surrounding the tip and formed by an annular wall which projects outwardly and is bent 70 over and back inwardly to form a contracted flame throat, and a central air chamber which enlarges as it approaches the reflector, means to close the back end of the chamber formed between the inner and outer 75 portions of said wall, there being air ports in the inner and outer portions of said walls arranged substantially as described.

7. In a miner's lamp, a dish shaped reflector having a flattened back, a base on 80 which the back is mounted, a burner tip leading outwardly through the center of the back, a guard surrounding the tip and formed by an annular double wall which extends outwardly to a point beyond the tip 85 where the walls join, the outer wall having air ports near its outer end, and the inner wall being shaped to form a bulbous chamber having air ports near its base.

8. A reflector having a back portion, a 90 marginal forwardly projecting convexly curved flange surrounding the back portion, a burner tip, and a forwardly projecting guard adapted to surround the burner tip, 95 there being air exhaust ports arranged around the base of said marginal flange and air supply ports arranged in the said guard.

9. A reflector having a flattened back wall, a burner tip, an outer marginal convexly curved reflector flange around said 100 back, and a central guard which surrounds and protects the burner tip, there being air exhaust ports near the outer margin of the back and air inlet ports in said guard.

10. A reflector having a flattened back 105 wall, a burner tip, an outer marginal convexly curved reflector flange around said back, and a central guard which surrounds and protects the burner tip and is formed by an annular wall reversely curved to the 110 said reflector flange, there being air exhaust ports near the back of the reflector.

In testimony whereof I affix my signature.

ARTHUR B. MITCHELL.
